UNITED STATES PATENT OFFICE.

JOSEPH BIJUR, OF NEW YORK, N. Y.

LIGHTING SYSTEM FOR AUTOMOBILES.

1,197,532.

Specification of Letters Patent. Patented Sept. 5, 1916.

Application filed August 26, 1911. Serial No. 646,190.

To all whom it may concern:

Be it known that I, JOSEPH BIJUR, a citizen of the United States, residing at New York, in the county of New York and State of New York, have invented certain new and useful Improvements in Lighting Systems for Automobiles, of which the following is a full, clear, and exact description, such as will enable others skilled in the art 10 to which it appertains to make and use the same.

This invention relates to circuit-varying devices, and with regard to the more specific features thereof, to devices of this nature in connection with electrical regulating and lighting systems.

One of the objects thereof is to provide an electrical regulating system of accurate and reliable action.

Another object is to provide an electrical system comprising a vibratory circuit-interrupter in which practical and automatically acting means are provided to prevent injury to the parts.

Other objects will be in part obvious and in part pointed out hereinafter.

The invention accordingly consists in the features of construction, combinations of elements and arrangement of parts which 30 will be exemplified in the construction hereinafter set forth, and the scope of the application of which will be indicated in the following claims.

In the accompanying drawing, in which 35 is shown one of various possible embodiments of this invention—Figure 1 is a diagrammatic plan of a system; Fig. 2 is a side elevation of switching mechanism, certain parts being removed in order to show 40 the construction more clearly; and Fig. 3 is a sectional end view of the same, taken substantially on the line $x-x$ of Fig. 2.

Similar reference characters refer to similar parts throughout the different views 45 of the drawings.

Referring now to Fig. 1 of the drawing, there is shown a generator 1 provided with a shunt field 2, which has serially connected therewith a resistance element 3 and 50 a coil 4 upon the main switch. Mains 5 and 6 lead from the generator to a storage battery 7 and lamps 8 connected in parallel, as shown. Main 6 passes through a series coil 9 upon a vibrator controlling magnet 10, 55 and thence through a series coil 11 upon the

vibrator magnet 12, from which it leads to the coil 13 upon the main switch. A voltage coil 14 is wound upon magnet 10 to act normally with a compounding effect with respect to coil 9 and a second voltage coil 60 15 is provided upon the magnet 12. The main switch is provided with a voltage coil 16, and a resistance element 17 is connected in parallel with the generator field.

As diagrammatically indicated in Fig. 3 65 of the drawing, there is provided at 18 a lamp switch for connecting or disconnecting the lamp load with the battery or generator. There is also provided a reversing switch 19 whereby the connections between the battery leads and mains 5 and 6 are reversed, and the relation of these switches and connections therebetween is best shown in Figs. 2 and 3 of the drawing. Switch 18 may be 70 of any desired type and is here shown as comprising a movable contact 20 which assumes one of two alternative positions, respectively making and breaking connection between the contacts 21 and 22 connected in the conductor leading from the battery to 75 the lamps. It is to be understood that, in practical use, the switch 18 preferably takes the multiple contact form, so as to permit, in the case of automobile lighting, for example, the connection of the tail lamp by 80 itself or the tail lamp and head lights or other combinations. The spindle of this switch is actuated by a button 23 and is continued, as shown at 24, through the bracket 25 upon which the switches are mounted and 85 terminates in a worm 26. This worm meshes with a worm wheel 27 on the spindle 28 of the reversing switch 19. The latter is of the well-known type provided with a spindle which, upon being turned, distorts a spring 90 to such a degree that it suddenly snaps a pair of relatively insulated short circuiting members out of engagement with two pairs of stationary contacts and into such 95 position as to connect these contacts in a reverse manner. The details of switches of this nature are well known and form no part of the present invention, but it may be noted that as the spindle 28 is rotated it intermittently reverses the connections between the battery 7 and the generating and regulating system.

Recurring to Fig. 3 of the drawing, it is to be noted that the general action of the regulating apparatus is as follows:—The 100

magnets 10 and 12, respectively, control the spring-retracted vibratory armatures 29 and 30, which, in the position shown in the drawing, rest against stationary contacts, 5 thus completing a shunt about the resistance element 3. This shunt comprises the serially disposed elements, conductor 31, vibrating contact 29, conductor 32, vibrating contact 30 and conductor 33. If either magnet 10 or 12 10 attains sufficient field strength to attract its corresponding vibratory armature against the force of the retracting spring, this shunt will be broken and the resistance 3 thrown into circuit in series with the field of the 15 generator, thus weakening the latter. Upon this occurring the magnet which has attracted its armature will be similarly weakened and the armature retracted against its stationary contact, thus again completing the 20 shunt about resistance 3. This action may be repeated so as to result in a vibration of the armature at a greater or a less rate with a corresponding regulation of the generator output. It will be noted that the flow of 25 current through the shunt about resistance 3 is unidirectional as long as the direction of drive of the generator is unchanged, unless other means are provided for affecting this direction of flow. Such a flow of current permits the deposition upon one of 30 each pair of vibratory contacts of a minute mass of metal which interferes mechanically and electrically with the action of the vibrator. This action also takes place in 35 connection with other automatically controlled and frequently operated contacts, as in the main switch, and is harmful at such points, although particularly injurious at the contacting surfaces of a regulating vi- 40 brator. If the current be reversed, however, there is a reversal of this action which not only tends to prevent further injury to the contacts, but in a measure removes that already done.

45 The operation of the above-described embodiment of this invention is substantially as follows: Assuming that the generator be charging the battery and that the lamp load is thrown on, this manipulation of the 50 switch 18 acts, through spindle 24, to turn the spindle 28 throughout a small angle. If the lamps be turned off the further rotation of spindle 24 will occasion a further movement of spindle 28 and at a certain point 55 after, in this embodiment, a considerable number of actuations of the lamp switch 18, the reversing switch 19 will be operated and the connections between the battery and generator system reversed. When this ac- 60 tion takes place there is a tendency of the battery to discharge back through the armature circuit and there is an instantaneous surge of current which may tend to reach a high value, but the reversal of the generator field will cause the generator to build up 65

with the reversed polarity. This surge of current acting through coil 9 will open the shunt about resistance 3 by the action of the vibrator of magnet 10, thus weakening the field and tending to hinder the proper picking up of the generator to meet the reversed battery connections. Under these conditions, however, the coil 14 becomes of reversed polarity and acts differentially with respect to coil 9, thus cutting down the 70 resultant field of the magnet 10 and causing the shunt about resistance 3 to close. It may be noted that the reverse of polarity of the coil 14, as well as of the generator field, is due to the fact that with the battery connections reversed and with the momentary surge of current resulting therefrom, the battery will determine the direction of flow through these coils rather than the generator. Although the generator voltage may 75 be greater than that of the battery prior to reversal, nevertheless, it will drop off when the above rush of current occurs much more quickly than will that of the battery, due partly to the limited output of energy of 80 which it is capable and partly to the breaking of the shunt about resistance 3, as above stated. The generator will accordingly build up with reversed polarity and the flow of current through the several circuits, includ- 85 ing the shunt about resistance 3, is reversed. The current being reversed in coil 9 and the generator thus built up, permits this coil to again act cumulatively with respect to coil 14 and the regulation proceeds as before. 90 It is to be noted that this reversal is automatically accomplished, in the ordinary use of the system, by the actuation of the lamp switch, and hence all contacts are effectively protected without the need for supervision. 95 It will also be noted that by the action of the parts as herein set forth, the battery may be connected in any manner found most convenient or efficient without interfering with the action of the generating and regu- 100 lating system.

105 As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

110 Certain features herein shown and described are shown, described and claimed in my co-pending application Serial No. 598,532, filed December 21, 1910, and accordingly are not claimed herein. These 115 features include the arrangement of a resistance in parallel with the field winding, and certain features of the construction and action of the generator regulator devices.

- Having described my invention, what I claim as new and desire to secure by Letters Patent is:
1. In an electrical system for automobiles, in combination, a generator having a shunt field winding, a pair of coacting contacts, means operatively related to said contacts and said winding to vary the current in said winding as said contacts are moved into and out of engagement, a regulating coil, a vibratory member controlled by said coil and controlling the engagement of said contacts, a device adapted to be manually actuated at will and upon actuation to perform an independent function in the operation of said system, and means connected with said device and adapted to reverse the direction of current through said contacts as said device is actuated.
  2. In an electrical system for automobiles, in combination, a source of current, an electric circuit connected with said source of current and comprising a pair of coacting contacts connected therein, means adapted rapidly to move said contacts into and out of engagement one with another, a device adapted to be actuated at will, and means connected with said device adapted upon its actuation to reverse the direction of current through said contacts and adapted simultaneously to perform another function in the system.
  3. In apparatus of the class described, in combination, a generator having a shunt field winding, a pair of coacting contacts, means operatively related to said contacts and said field winding to vary the current in said field winding as said contacts are moved into and out of engagement, a regulating magnet comprising a voltage coil and a current coil, a vibratory member controlled by said magnet and controlling the engagement of said contacts, and means adapted to reverse the direction of flow of current through said contacts and leave the relative polarities of said coils unchanged.
  4. In apparatus of the class described, in combination, a generator having a shunt field winding, a resistance element in series with said field winding, a shunt about said resistance element comprising a pair of coacting contacts, a regulating magnet comprising a voltage coil and a current coil, a vibratory member controlled by said magnet and controlling the engagement of said contacts, and means adapted to reverse the direction of flow of current through said contacts and leave the relative polarities of said coils unchanged.
  5. In apparatus of the class described, in combination, a shunt-wound generator, a storage battery adapted to be charged thereby, means adapted to act upon the field of said generator to limit its output, and means adapted to modify the action of said cur-
  - rent-limiting means upon the connections between said battery and said generator being reversed.
  6. In apparatus of the class described, in combination, a shunt-wound generator, a storage battery adapted to be charged thereby, a current coil, means acted upon by said coil tending to cut down the field strength of said generator as its output becomes excessive, and means comprising a voltage coil adapted to modify the action of said current coil upon the connections between said battery and said generator being reversed.
  7. In apparatus of the class described, in combination, a generator, a storage battery adapted to be charged thereby, a pair of coacting contacts, means operatively related to said contacts and the field of said generator to adapt it to weaken said field as said contacts are separated, a vibratory member controlling the engagement of said contacts, a current coil controlling said vibratory member, means adapted to reverse the connections of said generator and said battery, and means adapted to modify the action of said current coil as said connections are reversed.
  8. In apparatus of the class described, in combination, a generator, a storage battery adapted to be charged thereby, a lamp, a lamp switch adapted to connect said lamp with said battery, and means adapted to reverse the connections between said battery and said generator as said lamp switch is operated.
  9. In apparatus of the class described, in combination, a generator, a storage battery adapted to be charged thereby, a lamp, a lamp switch adapted to connect said lamp with said battery, a reversing switch interposed in the connections between said battery and said generator, and an operative connection between said lamp switch and said reversing switch whereby said reversing switch is operated by the action of said lamp switch.
  10. In apparatus of the class described, in combination, a generator, a storage battery adapted to be charged thereby, a lamp, a lamp switch adapted to connect said lamp and said battery and comprising a spindle, a reversing switch interposed in the connections between said generator and said battery and comprising a spindle, and a worm and wheel connection between said spindles whereby said reversing switch is operated upon said lamp switch undergoing a plurality of actuations.
  11. In apparatus of the class described, in combination, a generator having a shunt field winding, a pair of coacting contacts, means operatively related to said contacts and said field winding to vary the current in said field winding as said contacts are moved into and out of engagement, a regulating

42
5 magnet comprising a voltage coil and a current coil, a vibratory member controlled by said magnet and controlling the engagement of said contacts, means adapted to reverse the direction of flow of current through said contacts and leave the relative polarities of said coils unchanged, a device comprising a movable member and adapted to perform an independent function by the movement of 10 said member, and an operative connection between said member and said reversing means.

12. In apparatus of the class described, in combination, a shunt-wound generator, a 15 storage battery adapted to be charged by said generator, a lamp, a lamp switch adapted to connect said lamp with said battery, means adapted to act upon a field circuit of said generator to limit the output of said 20 generator, means adapted to modify the action of said output-limiting means upon the connections between said battery and said generator being reversed, means adapted to reverse the connections between said battery and said generator, and an operative connection between said lamp switch and said reversing means.

13. In apparatus of the class described, in combination, a generator, a storage battery 25 adapted to be charged thereby, a pair of co-

acting contacts, means operatively related to said contacts and a field circuit of said generator to adapt it to weaken said field as said contacts are separated, a vibratory member controlling the engagement of said contacts, a current coil controlling said vibratory member, means adapted to reverse the connections of said generator and said battery, a lamp, a lamp switch adapted to connect said battery with said lamp, and an operative connection between said lamp switch and said reversing means. 35 40

14. In an electrical system for automobiles, in combination, a source of electric current; a pair of co-acting contacts; means adapted to lead current from said source through said contacts; an electro-magnet; a vibratory member controlled by said electro-magnet and controlling the engagement of said contacts; and a device adapted to 45 perform an independent function from the operation of said system and adapted to reverse the direction of current through said contacts by its use. 50

In testimony whereof I affix my signature, in the presence of two witnesses.

JOSEPH BIJUR.
